Atty.

UNITED STATES PATENT OFFICE

HAROLD L. DE LISLE, OF CHICAGO, ILLINOIS

SHALLOW DRAWER CONTAINER FOR SHEETS

Original application filed August 1, 1928, Serial No. 296,695. Divided and this application filed August 29, 1929. Serial No. 389,291.

These improvements relate to containers in the form of drawers associated with each other in a cabinet and designed to hold such sheet material as tracings, blueprints, etc. 5 found in drafting rooms.

This application is a division of my copending application filed August 1, 1928 as Ser. No. 296,695 on container for relatively large sheets.

10 One object of the invention is to reduce the wastage of space in filing cabinets for such material. It is found inconvenient to handle in one bunch or mass more than approximately one hundred sheets of the kind referred to. 15 The practice prior to my inventions has been to file that number of sheets in drawers not less than two inches deep, and thus considerably more than half of the drawer space is wasted. According to these improvements 20 the depth of the drawers may be reduced greatly, and in my practice their depth is one inch. A sheet-metal drawer having only one-inch deep sides and ends and having large horizontal dimensions involves consider- 25 erations of construction not present in say a two inch drawer, and one feature of the present invention is directed to drawer construction.

When these drawers contain the practical- 30 ly permissible amount of sheet material they are quite heavy, and another feature of the invention is directed to ease and convenience in operation.

In the accompanying drawing Figure 1 35 shows fragmentarily in side elevation a plurality of drawers in a cabinet also fragmentarily shown;

Fig. 2 is a fragmentary top plan of any one of the drawers of Fig. 1;

40 Fig. 3 is a further enlarged and longitudinal sectional view, as on the line 3-3 of Fig. 2;

Fig. 4 is a fragmentary rear elevation, on the scale of Fig. 3, at one of the rear rollers; 45 and

Fig. 5 is a fragmentary vertical section showing the construction at the sides of the drawer and portions of the cabinet at say the line 5-5 of Fig. 2.

50 Referring to Fig. 1 the cabinet has a rear

end wall 10 and side walls 11 while the front remains open for the insertion of the drawers. The adjacent ones of these drawers marked respectively 14 to 22 inclusive are in close association with each other and are ar- 55 ranged one above the other in series. They are carried for forward and rearward sliding movements by guiding-and-supporting means in the form of angle irons 25, seen in cross view in Fig. 5.

60 Each drawer illustrated has bearing mem- bers, preferably antifriction elements, shown as rollers 26 and 27, each thereof extending above the plane of the surfaces defining the top of these open top drawers respectively. 65

The drawer 20 is shown as being drawn out- 70 wardly to some extent. Note that the roller 26 of the drawer 20 is in contact with the sub- stantially flat bottom wall 28 of the drawer above it marked 19, and that the roller 27 of the drawer 21 is at the same time in contact with the flat bottom wall 28 of the drawer marked 20. No matter which drawer is with- 75 drawn its roller 26 and the roller 27 of the drawer below it operate in the same way to support the drawer partially drawn out. The effect is to render the operation of the drawer very easy.

80 The guiding-and-supporting elements 25 are so arranged that they are just about or barely in contact with the side marginal por- 85 tions of the drawers respectively when the drawers are in closed position, as they are for the most part in Fig. 1, whereby both the rollers 26 and 27 of any given drawer are in actual contact with the bottom walls respec- 90 tively when the drawers are in closed position. The aim in this respect is to have the weight of the respective drawers on the rollers, but with the angle iron cleats as 25 so substantial- 95 ly close to the under surfaces of the respective drawers that when any drawer is removed wholly or partially from the cabinet the drawer above will immediately rest on the supports as 25.

In the preferred arrangement the rollers are at the extreme end portions of the draw- 100 ers where there is strong reinforcing. That arrangement has other advantages but it is

clear that rollers could be positioned along the sides.

The close arrangement of the cleats as 25 with the margin of the drawers is desirable further to prevent sagging of the drawers through a period of time. If the top surface of the rollers 26 and 27 be but slightly higher than the sliding surface of the cleats 25 next above them respectively the desired result will be obtained. When the drawer is withdrawn a considerable distance the overbalancing of the front end with respect to the rear end brings the roller 26 more strongly in contact with the bottom of the drawer above.

15 Each drawer has a pair of handles or pulls 29 secured as by screws 29a at the front end.

Fig. 2 shows that there are three such rollers 26 and three of the rollers 27 at spaced-apart intervals across the rear and front marginal portions respectively of each of the drawers. It has been mentioned that these drawers are of very considerable size in the fore-and-aft and lateral directions, and such a plurality of rollers as shown by Fig. 2 is 20 highly advantageous in the larger size drawers. More narrow drawers would suitably have two pairs of such rollers, while it is conceivable that a peculiarly narrow yet long drawer might be suggested for a particular 25 purpose and in which a single roller at the front and rear would suffice.

In the drawer construction illustrated the bottom wall 28 is turned up to form side walls as 30, the end wall 31 and the front wall 32.

35 Referring to the right hand end of Fig. 3 a channel formed from sheet-metal having a normally vertical part 34, a top part 35, and a bottom part 36 fits upon the bottom wall 28 at 28a and upon the end wall 32. The 40 bottom wall 28 is pressed inward slightly at 28a to accommodate the flange-like part 36. This reinforcing member 34-35-36 is 45 strongly secured to the adjacent parts as by spot-welding, and this spot-welding is done before the reinforcing member next to be mentioned is applied. This further reinforcing member has a bottom flange-like part 38, a vertical part 39 and a forwardly extending part 40 reaching to the vertical end 50 wall 32, and the upper walls 35 and 40 overlap each other to their full extents respectively. This auxiliary support 38-39-40 is spot-welded to the bottom 28. It may also be spot-welded to the part 35, but I find that 55 to be unnecessary where I have a plurality of screws, shown at 41 Fig. 2, holding the roller frames, these screws being threaded into the upper flange 40.

The construction at the right hand end of 60 Fig. 3 as thus described provides a hollow rim substantially rectangular in cross view and extending from side to side of the drawer at its front end. Assuming the drawer of Fig. 3 to be one inch in height, the fore- 65 and-aft proportions of the rim are indicated,

Note that the bottom wall 28 is strongly reinforced at its front end portion by the flange-like parts 38 and 36 spot-welded to the bottom 28.

Turning to the left hand end of Fig. 3 the end wall 31 is turned rearward to form the flange-like upper wall 31a. (See Figs. 2 and 4.) There is rigidly secured to the wall 31 a channel iron of sheet-metal having a vertical part or base 43, a lower flange-like part 44 and an upper flange-like part 45, the flange 44 being on the plane of the bottom 28. These upper and lower flanges are parallel with each other and extend, as does the base 43, from side to side on the end wall 31, the base 43 thus being coextensive with the wall 31.

The upper flange 45 interfits with the top wall 31a and is preferably spot-welded thereto at intervals. With the double thickness of metal at the top, namely the flange-like parts 31a and 45, taken with the rest of the construction shown the strength of this reinforcing member is sufficient.

Turning to Fig. 5 showing the construction 100 at the sides of the drawer, secured to the side wall 30 is a reinforcing member substantially rectangular in cross view and having a normally vertical wall 48 coextensive with the wall 30, a top wall 49 and a bottom wall 50, the upper and lower walls 49 and 50 having extensions 511 and 521 respectively which are on normally vertical lines and are directed toward each other, but they do not come together, leaving a gap at 54 through which the electrode is inserted for spot-welding the walls 48 and 30 together. The flanges 511 and 521 strongly reinforce the construction and the reinforcement thus provided for the sides affords the desired strength and rigidity.

The roller construction is the same at both ends and will be given the same reference characters except for the rollers themselves. There is a rectangular open frame 60, Fig. 4, having side extensions 51 through which the screws 41 project to be threaded into the flange 45 at the left hand end of Fig. 3 and the flange 40 at the right hand end thereof. The frame 60 fits between the walls 32 and 39 at the right hand end of Fig. 3 and fits against the base 43 at the left hand end of that figure. These frames 60 therefore reinforce to some extent the rest of the construction. The rollers 26 and 27 are mounted on shafts 63, Fig. 4, extending rotatably through the uprights of the frame 60.

Such a shallow drawer not only effects savings in construction but, importantly, in the filing space necessary for a given number of blue-prints, tracings, and the like, this latter being a feature of unusual importance when the hundreds of thousands of such sheets to be found at a given engineering office are considered. According to my various im- 130

provements, some of which are shown in my said copending application, I am able to provide much greater convenience to the user and safety to the material in the handling of such sheet material than has heretofore been known; but it may be mentioned that sheet material in the present one-inch drawer, to the full number of such sheets practically possible, namely about one-hundred, may be handled far more conveniently and advantageously than according to prior practices, one feature of advantage being in the extreme shallowness of the drawer.

I am aware that roller-bearing devices have been suggested heretofore in drawer construction, but I am not aware that this particular type or character of roller-bearing has been known prior to my invention thereof. It is of peculiar value in connection with such relatively large and shallow drawers as I have herein referred to.

I contemplate as being included in these improvements all such changes, variations, modifications and departures from what is thus specifically illustrated and described as fall within the scope of the appended claims.

I claim:

1. In combination, walls forming a cabinet, a pair of open-top drawers having substantially flat bottom walls respectively, said drawers being adjacent to each other and positioned one above the other in the cabinet, guiding-and-supporting means at the sides of the drawers respectively, the lower drawer having a roller at the rear end portion thereof and arranged to contact the bottom wall of the upper drawer when the lower drawer is drawn outwardly relative to the upper drawer.

2. In combination, walls forming a cabinet, a pair of open-top drawers having substantially flat bottom walls respectively, said drawers being adjacent to each other and positioned one above the other in the cabinet, guiding-and-supporting means at the sides of the drawers respectively, the lower drawer having a roller at its front end portion and arranged to be contacted by the bottom wall of the upper drawer when the upper drawer is drawn outwardly relative to the lower drawer.

3. In combination, walls forming a cabinet, a plurality of open-top drawers having substantially flat bottom walls respectively and being positioned one above the other in closely adjacent relation in the cabinet, guiding-and-supporting means at the sides of the drawers respectively, each drawer having a roller at its rear end portion and a roller at its front end portion, the arrangement providing that when any one of the drawers is drawn outward relative to a drawer immediately above it and a drawer immediately below it the rear roller of such drawer drawn outward contacts the bottom

wall of the drawer above while the bottom wall of such drawer drawn outward rests upon the front end roller of the drawer below.

4. A shallow drawer construction of sheet metal including a bottom wall turned upward substantially at right angles to form an end wall and then backward substantially at right angles to form a narrow upper wall, a bracing member having a part extending along the bottom wall adjacent to the end wall and a part extending upward alongside said end wall, said bracing member being rigidly secured to the bottom and end walls, there being a second bracing member rigidly secured to the bottom wall on the inner surface thereof and extending upward substantially parallel with the end wall and being spaced therefrom and extending thence forward adjacent to and in overlapped relation with said upper wall, forming a narrow double-thickness wall at the top, the construction thus forming a tubular body extending alongside one marginal portion of the drawer.

5. The combination of claim 4 hereof in which the double-thickness top wall has an opening, and there is a roller frame extending into said opening and secured to the drawer-construction parts adjacent thereto, and there is a roller carried by said frame and extending above said top wall.

6. A shallow sheet-metal drawer construction including a bottom wall turned upward substantially at right angles to form a side wall, and a bracing member rigidly secured to said side wall and being substantially coextensive therewith in the longitudinal and vertical directions, said bracing member having an upper extension and a lower extension, the lower extension being substantially at and in the plane of the bottom and the upper extension being substantially parallel with the lower extension and at the top edge of the drawer.

7. The combination of claim 6 hereof in which the upper extension of said bracing member has an opening and there is a roller frame secured to said bracing member at said opening, and there is a roller carried by said frame and extending through said opening and above the upper surface of said upper extension.

8. A side wall construction for a shallow sheet-metal drawer of the character described including a normally horizontal bottom wall having a side wall turned substantially vertically upward therefrom, and a bracing member having a part coextensive with the side wall and rigidly secured thereto, said bracing member having an upper extension and a lower extension, said extensions being normally substantially horizontal and being at the upper and lower edges of the drawer respectively, the upper extension being turned downward and the lower extension

being turned upward, said extensions being directed toward each other and having their ends spaced from each other.

9. A shallow sheet-metal drawer comprising a normally horizontal and flat bottom wall, side and end walls upturned from the bottom wall, and a reinforcing frame member at each of the side and end walls, each of said frame members having a top wall, a bottom wall and a side wall, the side wall of each of the frame members being rigidly secured to the adjacent wall upturned from the bottom wall.

10. In combination, two flat-bottom open-top drawers arranged one above the other, the lower drawer having a roller arranged to roll upon the bottom of the upper drawer when the lower drawer is moved outwardly relative to the middle drawer and the lower drawer having a roller arranged to be in contact with the bottom of the upper drawer when the upper drawer is moved outwardly relative to the lower drawer.

11. Walls forming an open-front cabinet, a plurality of drawers one above the other in a series in the cabinet, each of said drawers having bearing elements in contact with a next adjacent drawer of the series, the arrangement providing that one drawer communicates its weight through bearing elements to the drawer next below it, and means for supporting the drawers respectively whereby any given drawer is sustained when the drawer below it is withdrawn.
